UNITED STATES PATENT OFFICE.

ALFRED J. STECKER, OF DETROIT, MICHIGAN, ASSIGNOR TO FRED WARDELL, OF DETROIT, MICHIGAN.

ATTACHABLE BRUSH FOR VACUUM CLEANING-TOOLS.

1,179,049.

Specification of Letters Patent.

Patented Apr. 11, 1916.

Application filed July 22, 1915. Serial No. 41,278.

To all whom it may concern:

Be it known that I, ALFRED J. STECKER, a citizen of the United States of America, residing at Detroit, in the county of Wayne 5 and State of Michigan, have invented certain new and useful Improvements in Attachable Brushes for Vacuum Cleaning-Tools, of which the following is a specification, reference being had therein to the accompanying drawings.

The invention relates more particularly to that type of vacuum cleaning apparatus in which the suction tool is directly connected to the motor and fan casing, and it is 15 the object of the invention to provide means for quickly attaching or detaching a brush in relation to the mouth of the tool.

For removing dust from carpets, rugs and other fabrics, the most effective tool is one 20 having an open slot arranged in proximity to the surface to be cleaned. Such a construction is not as well adapted for the removal of dust from a floor or other impervious surface, nor would it always be effective 25 in detaching lint or other adhering matter from a fabric. On the other hand where the tool is provided with a brush this will operate to dislodge adhering dirt, but is easily clogged when used generally for 30 cleaning.

It is the object of the present invention to provide means for quickly converting the one type of tool to the other, this being particularly advantageous in machines having 35 permanently attached suction tools.

To this end the invention comprises the construction as hereinafter set forth.

In the drawings: Figure 1 is a sectional elevation of a vacuum cleaner to which my 40 improvement is applied; Fig. 2 is a perspective view of the suction tool with the brush removed; and Fig. 3 is a similar view showing the detached brush.

A is the motor and fan casing, and B is 45 the suction tool permanently attached thereto and having the elongated slotted mouth portion C. As shown, this is normally supported by rolls D at its opposite ends, so as

to extend in proximity to the surface to be cleaned. For converting this tool into one 50 of the brush type, I have provided an attachable brush E, preferably comprising parallel side bars F and F', each provided with depending bristles G. The bars F and F' are connected to each other by cross bars 55 H and H' at opposite ends thereof, which are so fashioned as to embrace the mouth portion of the tool and to hold the bristles adjacent to the longitudinal edges thereof. For securing the brush to the tool the latter 60 is preferably provided with ribs I, and the cross bars H and H' are bent to hook over the rib on one side as indicated at J. On the opposite side there is arranged a spring catch K for engaging with the rib which will 65 yield when the brush is pressed into engagement and will then snap into a retaining position.

With the construction described, when it is desired to attach the brush, this may be 70 quickly applied and the tool operated in the usual manner of brush tools. The engagement is such that in ordinary use the brush will not become accidentally detached, but whenever it is desired to remove it a slight 75 springing of the frame will detach the catches K and permit of removal.

What I claim as my invention is:—

1. In a brush attachment for suction nozzles, a brush bar, end bars carrying said 80 brush bar bent to embrace the mouth of the nozzle, and a yieldable catch for securing said end bars to the tool.

2. In a brush attachment for suction nozzles, parallel brush bars for engagement 85 at front and back of the nozzle and connecting end cross-bars for embracing and detachably engaging the nozzle.

3. A detachable brush for vacuum cleaning tools, comprising parallel brush bars, 90 end cross bars bent to embrace the mouth of the tool, and yieldable catches for securing said bent cross bars to the tool.

4. In a detachable brush for vacuum cleaning tools, a brush bar, members projecting 95 from the respective extremities of the brush

bar bent to embrace the mouth of the tool, and yieldable catches respectively carried by said members for securing said bent members to the tool.

5. In a detachable brush for vacuum cleaning tools, parallel brush bars, a connection between said bars engageable with the mouth of the tool, and a yieldable catch mounted

upon the connection to detachably secure the same to the tool.

In testimony whereof I affix my signature in presence of two witnesses.

ALFRED J. STECKER.

Witnesses:

JAMES P. BARRY,
PHYLLIS COBURN.
